UNITED STATES PATENT OFFICE.

FERDINAND SVOBODA AND CHARLES HOFMANN, OF CHICAGO, ILLINOIS.

DESIGN FOR A BARBER'S SIGN.

SPECIFICATION forming part of Design No. 21,782, dated August 23, 1892.

Application filed June 24, 1892. Serial No. 437,912. Term of patent 7 years.

To all whom it may concern:

Be it known that we, FERDINAND SVOBODA and CHARLES HOFMANN, both of Chicago, in the county of Cook and State of Illinois, have 5 invented and produced a new and original Design for a Barber's Sign, of which the following is a specification.

Reference is to be had to the accompanying drawings, forming a part of this specification, 10 in which similar letters of reference indicate corresponding parts in both the figures.

15 The design consists of the following elements, namely: the figure a, composed of the head and face of a man, which figure is in relief on the face of the sign, the figure b representing toweling gathered about the neck of the human figure a, a series of stripes or 20 panels c on the face of the sign and inclined from the longitudinal center of the same, and the shield d, having stars on its upper portion and arranged below the figure a.

We claim—

The design for a barber's sign, as shown.

FERDINAND SVOBODA.
CHARLES HOFMANN.
